UNITED STATES PATENT OFFICE.

GEORGE C. DRESSEL, OF NEW YORK, N. Y.

SIGNAL-LAMP.

SPECIFICATION forming part of Letters Patent No. 390,288, dated October 2, 1888.

Application filed March 9, 1888. Serial No. 266,655. (No model.)

To all whom it may concern:

Be it known that I, GEORGE C. DRESSEL, of New York city, New York, have invented a new and Improved Signal-Lamp, of which 5 the following is a specification.

This invention relates to various improvements in signal-lamps to be used by railroad employés.

The invention consists in the features of 10 improvement more fully pointed out in the claims.

In the accompanying drawings, Figure 1 is a side view of my improved lamp. Fig. 2 is a back view of part of the same. Fig. 3 is a 15 vertical section on line x x , Fig. 2. Fig. 4 is a face view of the removable glass, and Fig. 5 a side view of the flange of the lens.

The letter a represents the body of a lamp, having, as usual, a white lens, b , known as 20 "bull's-eye" or "semaphore," within two of its sides. Each of these lenses is surrounded by an outwardly-projecting tapering flange, c . As is well known, railroad signal-lamps must be so constructed that they can display differently-colored lights, such as green, red, &c.

I propose to secure the colored glass to the flange in front of the white lens. By this construction ready access to the glass is had, and, moreover, as the flange c is tapering, the 30 size of the colored glass may be made larger than the size of the white lens. Thus the volume of colored light emitted from the lamp is greatly increased.

The colored pane consists of a preferably 35 round piece of glass, d , Fig. 4, surrounded by a frame, e , having the pin e' and pin or eye e^2 diametrically opposite one another.

The flange c of the lamp a has a slot, c' , and a bayonet-slot, c^2 , also diametrically opposite

one another. The slot c' is traversed by a 40 bent spring, c^3 , as shown.

In order to affix a colored glass to the lamp, the pin e' is introduced into slot c' , and the shank of eye e^2 is introduced into bayonet-slot c^2 , the spring c^3 preventing rattling. Thus it 45 will be seen that the introduction of the glass d can be rapidly effected, while its removal is of course just as simple.

To provide a storage-chamber for the colored lights not in use, the rear side of the lamp 50 a is made with double walls. Between these walls there is formed a pocket provided with the door f , as shown.

In order to secure the lamp to a supporting post or bracket, it is encircled at its neck h , 55 above foot g , by a pair of jaws, i , terminating in the heads i' .

What I claim is—

1. The combination of lamp a , having lens b , and outwardly-projecting slotted flange c , 60 with the glass d , having frame e , and adapted to be inserted in the flange of the lens-frame immediately in front of the lens, the frame e being provided with pins adapted to be received by said slotted flange, substantially as 65 specified.

2. The combination of lamp a , having lens b and outwardly-projecting slotted flange c , with the glass d , having frame e , and adapted 70 to be inserted in the flange of the lens-frame immediately in front of the lens, the frame e being provided with the pin e' and eye e^2 , and with the spring c^3 , substantially as specified.

GEO. C. DRESSEL.
